(57) **CLAIM**

The ornamental design for a post anchor as shown and described.

DESCRIPTION

FIG. 1 is a top perspective view of a post anchor showing the new design;

FIG. 2 is a bottom perspective view thereof;

FIG. 3 is a front view;

FIG. 4 is a rear view;

FIG. 5 is a left side view;

FIG. 6 is a right side view;

FIG. 7 is a top view; and,

FIG. 8 is a bottom view.

The surface shading is intended to depict surface contour and forms no part of the claimed design.
